UNITED STATES PATENT OFFICE.

GEORGE S. FRAZIER, OF SEBRING, OHIO.

CHAIR-SEAT PAD OR CUSHION.

Application filed December 17, 1923. Serial No. 681,292.

To all whom it may concern:

Be it known that I, GEORGE S. FRAZIER, a citizen of the United States, residing at Sebring, in the county of Mahoning and State of Ohio, have invented new and useful Improvements in Chair-Seat Pads or Cushions, of which the following is a specification.

This invention relates to cushioned chair seat pads, and one object of the invention is 10 to provide a molded sponge rubber pad which is comfortable and durable, capable of being washed without injury to maintain it in a sanitary condition, which will retain its shape and position on the chair, 15 which will not pack or wear in spots, and which will not unduly wear and gloss the clothes.

Another object of the invention is to provide a cushioned seat pad which may be 20 furnished with a felt top so combined with the rubber body of the pad as to prevent it from loosening or peeling off and which will give all the advantages of a felt pad with that of a base possessing maximum 25 cushioning qualities.

The invention consists of the features of construction, combination and arrangement of parts, hereinafter fully described and claimed, reference being had to the accompanying drawing, in which:—

Figure 1 is a top plan view of one form of cushion seat pad embodying my invention.

Figure 2 is a bottom plan view of the same.

Figure 3 is a transverse sectional view thereof, taken, for example, on line 3—3 of Figure 1.

In carrying my invention into practice, 40 I provide a chair seat pad or cushion 1 formed of a body of molded rubber. The molded composition employed is that known as sponge rubber, producing a pad body which is strong, durable and gives a highly 45 desirable degree of cushioning action without undue compression and distortion from its normal shape. Such a body will, therefore, provide an easy and comfortable seat surface, having the properties of retaining its shape and which will not pack to a greater degree of density or wear off in spots. The lower surface 2 of this body which engages the seat on which it is to 50 repose is provided with fine longitudinal and transverse ribs, molded therewith, and producing a surface finish simulating that

of a coarse textile fabric, such surface 2 thus acting as a friction surface having a certain degree of suction action, owing to the elasticity of the sponge rubber body, 60 whereby through the combined action of friction and suction slipping of the pad out of its proper position on the chair seat will be effectually prevented.

The pad is so constructed as to give the combined advantages of a cushioned sponge rubber pad with that of a felt pad. To this end the pad is provided with a top surface layer 3 of felt or some other suitable equivalent soft, durable and more or less elastic fabric. 70 This felt layer may be comparatively thin and is incorporated with the rubber pad body in a substantially homogeneous manner. In applying the felt layer to the sponge rubber body, the bottom surface of 75 said felt layer is first primed with a proper amount of the liquid rubber composition which is rubbed or frictionized into the same; the top surface of the pad body is then coated with a suitable amount of the 80 same composition; the felt layer is then laid so that its coated face comes in contact with the coated face of the body, after which it is firmly pressed down in position so that the coated faces 3a thereof adhere or are 85 cemented together. This connection is then made permanent by placing the pad so formed into a heater and subjecting the same to vulcanizing temperature for a period of from forty-five to sixty minutes, 90 whereby the rubber composition uniting the pad body and felt will be cured or vulcanized so as to form a solid unit. The felt layer will thereby be secured to the pad body against any possibility of wrinkling, peeling or otherwise getting out of shape or becoming displaced, producing an exceedingly strong and durable type of article. The use of a felt surface gives an attractive finish and produces a satisfactory type of chair 95 seat pad which will not unduly wear or gloss the clothes of the user. The rubberizing of the felt also prevents its complete saturation with water, and accordingly the pad may be scrubbed or washed with soap or 100 water whenever it is desired to cleanse it and keep it sanitary without in any manner impairing the appearance or quality of the pad.

From the foregoing description, taken in 110 connection with the drawing, the construction of my improved chair seat pad will be

readily understood, and it will be seen that a type of pad is provided which will be soft and easy, and have a very desirable cushioning effect, and which at the same time will 5 not pack or spread, but will preserve its shape under all conditions of service, which may be washed and kept in a thoroughly sanitary condition, which may be manufactured and sold at a low cost, and which will 10 not slip upon the chair, thus avoiding the use of fastening means of any type for securing it in position.

Having thus fully described my invention, I claim:—

15 As a new and improved article of manu-

facture, a chair seat pad comprising a molded unitary, homogeneous, universally resilient body of sponge rubber having applied thereto a soft non-friction wear surface formed of a layer of felt partially impregnated with a rubber composition, such rubber composition being vulcanized to the upper surface of the pad body and permanently uniting the wear surface thereto. 20

25 In testimony whereof I affix my signature.

GEORGE S. FRAZIER.
